(57) **CLAIM**

The ornamental design for a guide for drawer of refrigerator, as shown and described.

DESCRIPTION

FIG. 1 is a perspective view of a guide for drawer showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a reference view thereof showing the state that the subject design has been installed inside the drawer of refrigerator; and

FIG. 9 is a perspective view thereof, in use condition;

FIG. 10 is a perspective view thereof, in an alternate use condition; and,

FIG. 11 is a perspective view thereof, in an alternate use condition.

The broken line in the figure drawings represents unclaimed environment only and forms no part of the claimed design.
